UNITED STATES PATENT OFFICE.

WILLIAM D. THOMPSON AND DAVID W. HAWKSWORTH, OF DETROIT, MICHIGAN,
ASSIGNORS TO HUTCHINS CAR ROOFING COMPANY, OF DETROIT, MICHIGAN, A
CORPORATION OF MICHIGAN.

CAR-ROOF.

1,198,791.

Specification of Letters Patent. Patented Sept. 19, 1916.

Application filed June 11, 1910. Serial No. 566,385.

To all whom it may concern:

Be it known that we, WILLIAM D. THOMPSON and DAVID W. HAWKSWORTH, citizens of the United States of America, residing at 5 Detroit, in the county of Wayne and State of Michigan, have invented certain new and useful Improvements in Car-Roofs, of which the following is a specification, reference being had therein to the accompanying drawings.

It is the object of the invention to obtain a construction of car roof, in which the maximum of strength is combined with a minimum of weight and at the same time, 15 one in which the depth or thickness of the roof structure is reduced to the minimum.

With these objects in view the invention consists in a construction as hereinafter set forth.

20 In the drawings: Figure 1 is a cross section through the roof on one side of the ridge. Fig. 2 is a longitudinal section on line $x-x$ Fig. 1. Fig. 3 is a section on line $y-y$ Fig. 1.

25 In the construction of car roofs it is usual to provide carlines which form the roof trusses and purlins extending longitudinally of the structure. The carlines sustain the roof load which is the principal stress to 30 which they are subjected.

As it is one of the objects of our invention to reduce the depth of the roof while maintaining its strength, we have selected for the carlines, a form of beam possessing the 35 greatest strength in proportion to its height, viz.: an I-beam. This beam A is bent at the center which is arranged above the ridge purlin B and at the eaves is secured to the plates C on opposite sides of the car. The 40 attachment between the beam and the plates may be formed by cutting away the upper flange and web of the beam and bending the lower flange to over-lap the side of the plate. At the ridge the beam is secured by a clip 45 preferably a U bolt E which embraces the beam, and passes downward through the ridge purlin.

50 F are the intermediate purlins which extend longitudinally of the roof and are preferably notched or gained at G to receive the base flange of the carlines. To avoid diminishing the strength of beam by cutting the flanges thereof, the purlins are clipped to the beams and as shown, these clips are in the 55 form of straps H which pass through slots

I in the web of the beam, these being located near the neutral axis where the removal of metal will not diminish the strength.

The roof frame just described, is one possessing great strength, while the maximum thickness is the depth of the beam plus the slight thickness of the purlins. To complete the roof the metallic span plates J are arranged to extend between the beams, being supported upon the upper faces of the 60 purlins. The plates J are provided at opposite sides with upturned flanges K and these are embraced by a weather cap L. As shown the cap L is of U shaped cross section fitting over the top flange of the I-beam and extending downward into proximity to the plates. The flanges K are preferably bent inward toward the web of the beam which operates as a stop to limit the lateral movement of the plates. There is however, sufficient clearance provided to permit said plates to move independently of each other to take 65 care of any distortion of the roof frame.

At the ridge the plates J are provided with upturned flanges M which are embraced by a ridge cap N and these ridge caps are secured by junction caps O arranged above the carlines and embracing both the carline caps and ridge caps. The caps O may be secured by upwardly extending studs 70 P which as shown are integral with the U bolts E and are arranged at the center thereof. These studs may also be used for securing the saddles Q for the running board. The plates J are secured at the eaves 75 by depending flanges R nailed or otherwise secured to the plate C.

It will be observed that the entire thickness of the roof structure is confined approximately within the space limits of the 80 carlines and on account of the shape of the beam employed, the height may be reduced to a greater extent than is possible with any other structure. It will also be observed that the roof sheets J do not rest 85 upon the metallic flanges of the beams but are supported solely by the purlins, which latter are sustained by their connections with the carlines. This diminishes wear as the purlins are formed of wood and will not 90 abrade the surface of the plates in contact therewith.

What we claim as our invention is:

1. In a car roof, the combination with carlines and purlins, of relatively-movable load- 110

supporting roofing sheets extending over a portion of said carlines and having flanged edges, said sheets being supported by said purlins out of contact with said carlines, 5 and said flanged edges forming a truss for sustaining the sheet intermediate the purlins.

2. In a car roof, the combination with a carline having a base flange, of a purlin 10 gained to receive said base flange so that the upper edge of said flange is positioned below the plane of the upper face of the purlin, and a relatively-movable metallic

load-sustaining roofing sheet having a flanged edge portion extending over said 15 base flange of the carline but out of contact therewith, said flanged edge forming a truss for sustaining the portion of said sheet between points of support.

In testimony whereof we affix our signatures in presence of two witnesses.

WILLIAM D. THOMPSON.

DAVID W. HAWKSWORTH.
